(57) **CLAIM**

The ornamental design for an electrical outlet, as shown and described.

DESCRIPTION

FIG. 1 is a front elevation view of an electrical outlet showing our new design;

FIG. 2 is a rear elevation view thereof;

FIG. 3 is a right side view thereof rotated 90 degrees clockwise;

FIG. 4 is a left side view thereof rotated 90 degrees counter-clockwise;

FIG. 5 is a bottom view thereof;

FIG. 6 is a top view thereof;

FIG. 7 is a bottom left front perspective view thereof; and, FIG. 8 is a top left front perspective view thereof.

The structural features depicted by broken lines have been shown for the purpose of illustrating portions of the electrical outlet that form no part of the claimed design.
